HIGH-LOW SUPPORT SKID

Frank Amer, United States Navy, La Mesa, Calif.

Application May 2, 1945, Serial No. 591,594

7 Claims. (Cl. 61—67)

(Granted under the act of March 3, 1883, as amended April 30, 1928; 370 O. G. 757)

This invention relates to a supporting skid and more particularly to a type providing both high and low support for boats.

It is customary to support boats for scraping, painting and overhaul by means of numerous blocks, jacks, trestles or other similar devices. Such support is slow and cumbersome to provide. The slipping of the blocks, jacks and trestles is a source of danger. The boat's being maintained at one elevation is inconvenient; the sides being too high, or the bottom too low, for ease of work. To work on a portion of the boat in contact with a support, much time is required to unstack and re-stack the support.

Objects of my invention are, therefore, to provide an improved support that is quickly and easily available for use; to promote to the safety of workmen working on the supported object by eliminating "stacked" means of support; to promote efficient working conditions by providing an improved support capable of supporting an object at a low level for work on its sides and at a higher level for work on its bottom; to provide an improved support having a multiplicity of supporting members allowing the lowering of individual elements of support to enable work to be done at the area of contact with the supported object; and to provide improved elements and arrangements thereof in a support of the character and for the purposes set forth.

In accomplishing these and other objects of the present invention, I have provided improved details of structure, the preferred form of which is illustrated in the accompanying drawing, wherein:

Fig. 1 is a perspective view of a high-low boat skid embodying the features of the present invention, showing supporting posts in a relaxed position, such position allowing the reception and support of a boat by transverse frames.

Fig. 2 is a perspective view of a high-low skid embodying the features of the present invention, showing supporting posts upwardly extended to engage and support a boat in an elevated position.

Referring more in detail to the drawing:

The high-low boat skid embodying this invention preferably consists of spaced longitudinal skid stringers 1 of a material strong enough to support the weight to be borne, having lower runner surfaces 2 terminating in upwardly curving portions 3. Transverse plates or frames 4, 5, and 6 are rigidly mounted on the stringers 1 in a substantially vertical position the frames having offset cut-out portions at their lower outer

ends to seat upon the stringers and be supported thereby. The frames are also provided with upper edge surfaces 7, 8, and 9 shaped to conform to the hull of the boat to be supported.

Wedge or gusset like braces 10, 11, 12, 13, and 14 are securely bolted or otherwise secured to the frames and stringers to give strength and rigidity to the transverse frames 4, 5, and 6.

Hinge blocks 15 are mounted on the stringers adjacent the frames and they, with lock supporting blocks 16, are secured to the frames 4, 5, and 6. The lock supporting blocks 16 are vertically arranged in pairs, the blocks being spaced a sufficient distance apart to admit therebetween and engage when in an extended position, supporting posts 17, 18, or 19, presently more fully described. The hinge blocks 15 and lock supporting blocks 16 are of the same thickness as the supporting posts 17, 18 and 19.

The supporting posts 17, 18, and 19 may be relaxed as shown in Fig. 1, or vertically extended as shown in Fig. 2 in response to the elevation desired for the supported boat.

The boat may be supported on the transverse frames 4, 5, and 6 or in an elevated position on posts 17, 18, and 19 of a number, size and material providing ample strength for support of the boat.

The extended ends of the posts 17, 18, and 19 and the upper edge surfaces 7, 8, and 9 of frames 4, 5, and 6 are padded substantially as shown to protect the bottom of a supported boat.

Hinges 20 pivotally mount the posts 17, 18, and 19 on the hinge blocks 15 so as to be vertically extensible. The removable hinge pins 21 permit the removal and substitution of the posts 17, 18, and 19 in correlation to the shape of the boat to be supported.

Posts 17 are preferably hinged to swing in the opposite direction from posts 18 and 19. By pivoting the posts in opposite directions, their folding moments oppose each other and tend to hold the posts in a vertical position when loaded. This tendency serves to supplement a function of the locking devices presently more fully described. It also provides a more compact arrangement of the legs when folded down.

Strap iron receivers 22 are firmly secured to the posts 17, 18 and 19 and similar, but oppositely arranged strap iron receivers 23 are firmly secured to the lock supporting blocks 16. Each of the receivers 22 and 23 has a transverse passage therethrough. The receivers 22 and 23 are so mounted as to have the transverse passage in the 55 outside receiver 23, the passage in the two re-

ceivers 22, secured to the posts 17, 18, and 19, and the passage in the inward receiver 23 coaxially aligned. Locking pins 24 are inserted through the co-axial passages to lock the posts in an upright position. The locking device consisting of the receivers 22 and 23 and pin 24 is in each case put a distance from the hinge to be locked, sufficient to provide strong supporting leverage.

Upper portions 25 of posts 19 are lockably articulated at 26 to posts 19 by hinge and locking device 27 similar in construction to those previously described, the principal difference being that the locking devices are secured to the inner faces or sides of posts 19, as shown in Fig. 2 while the hinges are secured to the outer faces thereof as shown at 28, Fig. 1. The upper portions 25 of the posts pivot in the opposite direction from the main bodies of the posts 19.

Operation

The operation of a high-low boat skid constructed as described is as follows:

When the sides of a boat are to be worked on, the posts 17, 18, and 19 are left in a relaxed position, as shown in Fig. 1. The boat is hoisted, then lowered into position on the transverse plates or frames 4, 5, and 6. The configuration of the upper edge surface 7, 8, and 9 of the frames 4, 5 and 6 serve to maintain the boat in an upright position.

When the bottom of the boat is to be worked on, it is again hoisted. The posts 17, 18, and 19 are raised to a vertical position and locked by passing the locking pins 24 through the co-axial passages in the receivers 22 and 23. The boat is then lowered onto the upwardly extending posts 17, 18, and 19.

As work on a boat bottom progresses, it becomes necessary to work on the boat at areas of contact with supporting posts. In such a case, the post in the way is unlocked by pulling out the locking pin 24 and the post is folded down out of the way. The boat is supported during such procedure by the multiplicity of remaining vertical posts. When the work on such an area is completed, the post is returned to position and locked by inserting supporting pin 24 in receivers 22 and 23 as previously described. Any one of the posts 17, 18, and 19 may so be lowered to remove it from a working area. In practice, it has been found that all posts lower easily except posts 18 supporting the bow of the boat. As posts 19 are pivoted aft, they tend to bind on the boat as a greater beam is encompassed. This difficulty has been obviated by providing posts 19 with the lockably articulated upper portions 25 hinged to fold forwardly as the posts fold aft, thus expediting the lowering and subsequent extending of posts 19.

To remove the posts 17, 18, and 19 and substitute other posts adapted to conform to the configuration of other types of boats to be supported, the hinge pins 21 are removed, the requisite posts inserted, and the hinge pins 21 returned to place.

It is apparent, therefore, that I have provided a high-low boat skid quickly and easily available for use; having improved safety features; providing both low and elevated supporting levels conducive to working efficiency; having a multiplicity of supporting members individually capable of being lowered for work in areas of contact; and having posts easily interchangeable permit-

ting the adaptation of the skid to support boats of various shapes in elevated position.

While I have shown but one embodiment of my invention, it is apparent that the device is susceptible to modification without departing from the spirit of the invention. I do not wish, therefore, to be limited by the disclosures set forth, but only by the scope of the appended claims.

The invention described herein may be manufactured and used by or for the Government of the United States of America for governmental purposes without the payment of any royalties thereon or therefor.

I claim:

1. A supporting skid comprising longitudinal skid stringers, a plurality of transverse frames mounted on the stringers adapted to receive and support an object in a low working position, said stringers and plates constituting a rigid foundation element, and a plurality of supporting posts pivotally mounted on the foundation element vertically extensible to provide elevated object support.

2. A supporting skid comprising longitudinal skid stringers, a plurality of transverse frames mounted on the stringers adapted to receive and support an object in a low working position, a plurality of supporting posts hinged to said transverse frames vertically extensible to provide elevated object support and capable of being lowered singly for work on the supported object at an area of contact therewith.

3. In a supporting skid of the character described, longitudinal skid stringers, a plurality of transverse frames rigidly mounted on the stringers adapted to receive and support an object in a low working position, a plurality of supporting posts hinged to said transverse frames vertically extensible to provide elevated object support and capable of being lowered singly for work on the bottom of the supported object at an area of contact, and cooperative means on posts and frames for holding the posts in upright position.

4. In a supporting skid of the character described, longitudinal skid stringers, a plurality of transverse frames rigidly mounted on the stringers in a substantially vertical position adapted to receive and support an object in a low working position, a plurality of supporting posts vertically extensible to engage and support the object in an elevated position, hinges to mount the supporting post to the transverse frames permitting the individual lowering of a post at a time to work on the supported object at an area of contact and the lowering of all posts at one time to rest the object on the transverse frames, removable pins for said hinges enabling the removal and substitution of posts to engage in conformity the configurations of the object to be supported, receivers on said posts and frames, and locking pins engageable with said receivers to lock the posts in extended position.

5. A boat skid comprising longitudinal skid stringers, a plurality of transverse frames rigidly mounted on the stringers in substantially vertical position adapted to receive and support a boat in a low position for convenience in working on its sides, and a plurality of vertically extensible supporting posts secured to the stringers and frames to engage and support the boat in an elevated position to facilitate work on the bottom of the boat, certain of the supporting posts having hinged upper portions expediting the vertical positioning of the supporting posts.

6. A boat skid comprising longitudinal skid

stringers, a plurality of transverse frames rigidly mounted on the stringers in substantially vertical position adapted to receive and support a boat in a low position for convenience in working on its sides, and a plurality of vertically extensible supporting posts secured to the stringers and frames to engage and support the boat in an elevated position to facilitate work on the bottom of the boat, certain of the supporting posts having hinged upper portions expediting the vertical positioning of the supporting posts, means for mounting the supporting posts on the transverse frames and permitting the lowering of individual posts to work on the boat at point of contact and the lowering of all posts to rest the boat on the transverse frames, removable pins for said hinges enabling the removal and sub-

stitution of posts to engage various types of boats to be supported, receivers on posts and plates provided to lock all hinges, and locking pins provided to engage said receivers and lock the hinges in extended position.

7. In a supporting skid, longitudinal skid stringers, a plurality of transverse frames mounted on the stringers adapted to receive and support an object in low working position, and a plurality of supporting posts pivotally mounted on the transverse frames vertically positionable to provide elevated object support, said supporting posts being pivoted so as to have opposing folding moments, which communicated through an object being supported, tend to maintain said supporting posts in an extended position.
